UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF NEW YORK, N. Y., A CORPORATION OF NEW JERSEY.

CAR BOLSTER AND SIDE BEARING.

Application filed December 14, 1921. Serial No. 522,284.

To all whom it may concern:

Be it known that I, ALLEN E. OSTRANDER, residing at Ridgewood, Bergen county, New Jersey, and being a citizen of the United States, have invented certain new and useful Improvements in a Car Bolster and Side Bearing, of which the following is a full, clear, and exact description, such as will enable others skilled in the art to which it 10 appertains to make and to use the same, reference being had to the accompanying drawings, which illustrate the preferred form of the invention; though it is to be understood that the invention is not limited to the exact 15 details of construction shown and described, as it is obvious that various modifications thereof within the scope of the claims will occur to persons skilled in the art.

In said drawings:

20 Fig. 1 is a partial vertical sectional view of a tank car showing my invention applied thereto;

Fig. 2 is a vertical sectional view of a part of the bolster shown in Fig. 1 taken 25 on the line 2—2 of Fig. 3;

Fig. 3 is a horizontal sectional view taken on the line 3—3 of Fig. 2, parts being broken away to show other parts more clearly;

Fig. 4 is a vertical sectional view taken 30 on the line 4—4 of Fig. 2, and

Fig. 5 is a plan view of a part of the bottom cover plate of the bolster.

It is the object of my invention to provide an improved body bolster construction having 35 diaphragms adapted to provide increased strength for the support of the load carried by the side bearings, a bottom cover plate of channel shape for part of its length so as to reinforce the bolster diaphragms 40 and side bearings fitting into the channel-shaped portion of the bottom cover plate and having anchor means for use in securing the car body to the underframe.

I have shown my improved body bolster 45 as applied to a tank car but it is to be understood that my invention is not limited to the type of car shown.

As illustrated, a tank 1 is carried upon saddle blocks 2, 3 supported upon an under- 50 frame comprising center sills 4, spaced by a filled piece 5 and joined by a cover plate 6, and bolsters 7. The bolsters 7, only one of which is shown in the drawings, comprise pairs of diaphragms 8 having tapering webs 55 9 and outwardly projecting flanges 10. The

upper and lower flanges 10 of the diaphragms 8 are joined by the top and bottom bolster cover plates 11 and 12, respectively, which extend across the center sills 4 and for a part of the length of the 60 diaphragms 8 on each side of the sills 4 and are riveted to the flanges 10. Secured to the upper flanges 10 by the rivets that secure the cover plate 11 thereto is a supporting casting 13 that carries the block 3 and 65 is provided with projecting flanges 14 that engage the block 2 and secure it in position on the cover plate 11.

The webs 9 of the diaphragms are reinforced by means of tapering inclined corrugations 15 that extend part way down from the top flanges and merge into the webs where the webs are secured to a channel-shaped portion of the bottom cover plate that projects into the space between the webs 70 9 of the diaphragms, the flange portions 16 of this channel-shaped portion being riveted to the webs 9 of the diaphragms and serving to reinforce the same while the web portion 17 of this channel-shaped portion serves as 75 a spacing element and stiffener for the webs 9. Mounted in the channel-shaped portion of the cover plate 12 and secured in position by the rivets 18 that secure the flange portions 16 to webs 9 is a side bearing 19 having a base portion 20 adapted to receive a wear plate 21 and extending beneath the bottom flanges 10 of the diaphragms to which it is secured by the bolts 22 that secure the wear plate 21 to the base portion 90 20. The base portion 20 is extended to provide an anchor portion 23 in which is fastened an end of a strap 24 that serves to hold the body 1 in position on the underframe. Integral with the base portion 20 95 are projections 25 that are spaced so as to fit between the flange portions 16 to which they are secured by the rivets 18 and are extended to form a tapered continuous reinforcing flange for the anchor portion 23. 100 Joining the projections 25 and integral with the base portion 20 and projections 25 is a reinforcing rib 26 having an inclined top portion that joins the upper portions of the projections 25 and is engaged with the web 105 portions 17 when the side bearing 19 is secured in position.

From the foregoing description it will be seen that I have provided a construction in which the loads carried by the side bearings 110

are borne by diaphragm webs reenforced in the line of the greatest stress and transmitted to the side bearings, in part, directly from the diaphragms and, in part, through 5 the connection of side bearing, bolster bottom cover plate and diaphragm webs by means of rivets in double shear. It will also be seen that I have provided a side bearing 10 that comprises an anchor means for the car body and which serves to reenforce the bolster.

What I claim is:

1. In a body bolster spaced diaphragms having vertical webs and bottom flanges and 15 a bottom cover plate having vertical portions riveted to said vertical webs and relatively horizontal portions riveted to said flanges.
2. In a body bolster, vertical diaphragms 20 having bottom flanges, a side bearing extending across below and upwardly between said diaphragms, vertical and horizontal rivets connecting the side bearings to webs and flanges of the diaphragms and a pocketed bottom cover plate interposed between the diaphragm flanges and webs and said side bearing.
3. In a bolster, a cover plate provided with a plate middle portion and channel-shaped 30 end portions adapted for contact with the webs and flanges of bolster diaphragms.
4. A bolster cover plate comprising a sheet metal middle portion and integral flanged channel-shaped end portions.
- 35 5. A bolster cover plate comprising a substantially flat middle portion and obliquely disposed pressed channel-shaped end portions with outstanding flanges.
6. In a body bolster, spaced diaphragms, 40 a side bearing extending below and connecting said diaphragms, in combination with a pocketed bottom cover plate also connecting the diaphragms and extending above said side bearing between said diaphragms.
- 45 7. In a bolster spaced flanged diaphragms, a combined side bearing and tank band anchor adapted to underlie a bottom cover plate between said diaphragms, horizontal and vertical rivets connecting the webs and 50 flanges respectively of said diaphragms and

the side bearing, and a pocketed bottom cover plate paralleling the webs and bottom flanges of said diaphragms.

8. In combination, a body bolster having a pocketed bottom cover plate, a side bearing 55 extending into the pocket and secured to both vertical and relatively horizontal faces thereof.

9. In combination, a body bolster having a pocketed bottom cover plate, a side bearing 60 extending into the pocket and a tank band anchor integral with said side bearing.

10. In a body bolster, spaced diaphragms, a pocketed cover plate joining said diaphragms and a side bearing extending into 65 the pocket in said cover plate.

11. In a body bolster, spaced diaphragms having corrugated webs and a cover plate having a channel-shaped portion connecting 70 said webs.

12. In a body bolster, spaced diaphragms having webs, a side bearing connected to said webs and corrugations in said webs extending from the connections of said side 75 bearings and diaphragms.

13. In a body bolster, spaced diaphragms having webs, a pocketed cover plate and a side bearing connecting said webs and tapering corrugations in said webs extending from the connections of said cover plate and 80 side bearing with said diaphragms.

14. In a body bolster, diaphragms having webs and a side bearing connected to said diaphragm, said webs being corrugated in the line of greatest stress from said side 85 bearing.

15. In a body bolster, spaced diaphragms, a cover plate connecting said diaphragms and having a channel-shaped portion fitting between said diaphragms and a side bearing 90 extending into the channel-shaped portion and engaging the web portion of said channel-shaped portion.

In witness whereof I have hereunto set my hand in the presence of two witnesses. 95

ALLEN E. OSTRANDER.
